E. MEYER.

STIRRING OR AGITATING APPLIANCE FOR PAINT CANS AND OTHER RECEPTACLES.
APPLICATION FILED MAR. 19, 1915.

1,178,171.

Patented Apr. 4, 1916.

UNITED STATES PATENT OFFICE.

ERNEST MEYER, OF TUXEDO PARK, NEW YORK, ASSIGNOR OF ONE-THIRD TO HERBERT W. GROGAN AND ONE-THIRD TO CHESTER E. MACDUFFEE, BOTH OF NEW YORK, N. Y.

STIRRING OR AGITATING APPLIANCE FOR PAINT-CANS AND OTHER RECEPTACLES.

1,178,171.

Specification of Letters Patent.

Patented Apr. 4, 1916.

Application filed March 19, 1915. Serial No. 15,427.

To all whom it may concern:

Be it known that I, ERNEST MEYER, a citizen of the United States, residing at Tuxedo Park, in the county of Orange and State of New York, have invented an Improvement in Stirring or Agitating Appliances for Paint-Cans and other Receptacles, of which the following is a specification.

My invention relates to a stirrer or agitator appliance for cans or other receptacles for paint or other material in which liquids contain solids in suspension and in which the heavier material settles to the bottom of the receptacle, and the object of my invention is to provide the receptacle with means capable of thoroughly re-mixing its contents.

The details of construction are hereinafter particularly described.

20 In the accompanying drawing—Figure 1 is an elevation, the receptacle being in section. Fig. 2 is a sectional plan view taken at about the line α , α , of Fig. 1. Fig. 3 is an inverted plan of the stirrer or agitator removed from the receptacle. Figs. 4 and 5, respectively, illustrate modifications in an attachment of the crank handle. Fig. 6 shows a modification in the plug, and Fig. 7 shows a modification in the cover. Fig. 8 is a view 30 of the cone and blades on a small scale taken at right angles to that shown in Fig. 1.

10 designates the body of the receptacle, which is preferably of cylindrical formation and may be made of tin, wood or any 35 other suitable material.

11 indicates the cover for the receptacle. In the preferred form of my invention, the cover 11 is depressed within the receptacle and at its center has a tubular downwardly 40 projecting portion 12 open at the top but having a bottom 13, provided with a central opening 14. This tubular projection is inferiorly screw-threaded. Where the cover is made of comparatively thin sheet metal, 45 the thread may be pressed therein.

15 indicates a plug exteriorly screw-threaded to screw into the tube 12. This plug may be hollow, as shown in Fig. 1, and provided with a central opening 16 in its 50 top and bottom in line with each other, or the plug may be solid, as shown in Fig. 6,

and provided with a vertical central opening 17, extending entirely through it. Between the bottom of the plug 15, and the bottom 13 of the tube 12, there is a gasket 55 18 of felt or other fibrous material.

The cover 11 is provided with a nozzle 19, provided with a removable cap 20. This nozzle is preferably located at a suitable distance on one side of the central tube 12. 60

The stirring or agitator appliance consists essentially of a vertical shaft extending through a central opening in the top of the receptacle and provided with a crank at its upper end, a substantially hollow cone 65 secured to the shaft within the receptacle and having a slot on two opposite sides, with vertically disposed inclined blades dividing the interior of the cone at one side of each slot. The blades are arranged eccentrically 70 to the slots and form two compartments in the cone; these blades extending above the top surface of the cone.

21 designates the vertical shaft, which in the construction of the receptacle shown in 75 Fig. 1, passes through the central openings in the plug, gasket and bottom of the tube 12, its lower end contacting with the bottom of the receptacle. The cone is preferably formed of two segments 22 and 23, which 80 are secured to the shaft 21, on opposite sides and joined at their upper ends by solder, or in any suitable manner, at a predetermined distance from the lower end of said shaft. These segments of the cone are curved at 85 their lower edges corresponding to the interior shape of the body of the receptacle and extending in close proximity to the inner surface of said body 10. At a predetermined distance from the point of their 90 connection with the shaft 21, each of the members 22 and 23 has a portion at one side cut out, forming oppositely disposed slots or openings 24 and 25 in the cone.

26 and 27 represent two agitators or stirring blades which at their inner ends are secured to the shaft 21 by solder or otherwise, and are also preferably soldered to the edges of the members 22 and 23, respectively, on opposite sides of the slots or openings 24 and 25. Each of these agitator or stirrer blades has a straight horizontal bot- 95 100

tom edge which extends to the outer bottom edge of the members 22 and 23, and the outer side edge of each blade extends upwardly above the top surface of the conical member a predetermined distance from which point the top edge of each blade is inclined toward the shaft 21, terminating in a point which is preferably slightly curved back over the top of the cone. These agitators or stirrer blades are preferably arranged and inclined eccentrically to the slots 24 and 25, and to accomplish this, I form tapered right angled bends 28, the straight vertical edges of which are secured to the shaft 21, thus spacing the horizontal bottom scraping edges 29 of the stirrer blades from the shaft, and inclining the blades from the bottom upwardly. This is best illustrated in the inverted plan view Fig. 3. The cone and stirrer blades are preferably made of sheet metal, but may be made of any other suitable material.

At the top of the shaft 21, which extends above the plug 15, there is a crank 30, by means of which the shaft and stirring device may be rotated. This crank may be formed integral with the shaft as shown in Fig. 1, or a separate crank handle may be employed detachably secured to the upper end of the shaft by screw-threads, as shown in Fig. 4, or the butt of the crank handle may have a square recess, and the upper end of the shaft be provided with a reduced squared portion to fit into such recess and be secured therein by a pin 31, as illustrated in Fig. 5. In either instance the crank or handle does not project above the upper rim of the cover, and therefore does not interfere with the packing of the receptacles, one upon another, for transportation or storage. The periphery of the flanged head of the plug 15 is preferably knurled or roughened to facilitate turning.

In cases where the receptacle is of heavy material or large size, intended to remain stationary or not to be packed with others, the cover 11 may extend across the top of the receptacle in a straight line, being provided with a central hub 32, having a vertical central opening 33 for the passage of the shaft 21, as illustrated in Fig. 7. In such cases, the parts 12, 15, and 18 may be dispensed with.

The bottom edges of the cone segments 22 and 23 and agitator blades 26 and 27 are on the same horizontal plane with the lower end of the shaft and in a normal condition all rest upon the upper surface of the bottom of the receptacle with the circular bottom edge of the cone and outer vertical side edges of the blades in close proximity to the inner surface of the body 10 of the receptacle; consequently when the crank 30 is rotated, any material adhering to the bottom or sides of the receptacle will be di-

rectly acted upon by the bottom and outer side edges of the agitator or stirring blades, and thoroughly admixed with the liquid.

The nozzle 19 provides for the filling of the receptacle and also for the discharge of the contents, the cap 20 being placed over the nozzle after the receptacle has been filled, and removed therefrom to allow for the discharge of the contents.

When the receptacle is to contain paints or other material, in which liquids contain solids in suspension, the material is poured into the receptacle in a thoroughly mixed condition through the nozzle 19 and after the desired quantity had been poured or the receptacle filled, the nozzle is closed by the cap. With material of such character after the receptacle has remained stationary a short time, the heavier substance settles to the bottom and the contents of the receptacle requires remixing before use. By the employment of my invention such re-mixing of the contents is accomplished in a most thorough manner. Upon moving the crank 30 to the right, the blades 26 and 27 at the same moment begin to agitate the material at the bottom and lower part of the sides of the receptacle, that portion of the material within the conical member being forced upward through the slots or openings 24 and 25 toward the center of the receptacle between the inclined surfaces of the blades and under surface of the cone while that portion of the material agitated by the outer vertical side edges of the blades 26 and 27 will be directed upwardly and over the inclined top edges of the blades and upon the upper surface of the conical member, and will thereby be directed upwardly toward the center of the receptacle.

It will be readily seen that the shaft 21 may be moved vertically in its bearings, so that the cone with the agitator blades may be drawn upward if desired to stir or agitate the contents of the receptacle other than at the bottom, or to scrape off any substance adhering to the sides of the receptacle above the point acted upon by the side edges of the blades when the stirrer rests upon the bottom of the receptacle. It will also be understood that when the stirrer rests upon the bottom of the receptacle, the lower edges of the agitator blades will scrape off any material adhering to the bottom of the receptacle upon being rotated by the crank 30.

The cover may, if desired, be secured to the receptacle by solder, or any suitable means.

The gasket 18 prevents leakage of the contents of the receptacle should the receptacle be tipped or overturned.

I claim as my invention—

1. In combination with a receptacle, a stirring or agitating appliance rotatable

within said receptacle consisting of a vertical shaft extending through a central opening in the top of the receptacle and provided with a crank at its upper end, a conical member secured to the said shaft within the receptacle and provided with elongated slots open at their outer ends on two opposite sides and agitator blades dividing the interior of the conical member at one side of each slot.

2. In combination with a receptacle, a stirring or agitating appliance rotatable and vertically movable within said receptacle consisting of a vertical shaft extending through a central opening in the top of the receptacle and provided with a crank at its upper end, a conical member secured to the said shaft within the receptacle and provided with elongated slots open at their outer ends on two opposite sides, and agitator blades dividing the interior of the conical member at one side of each slot.

3. In combination with a receptacle, a stirring or agitating appliance, rotatable within said receptacle, consisting of a vertical shaft extending through a central opening in the top of the receptacle and provided with a crank at its upper end, a conical member secured to said shaft within the receptacle and provided with elongated slots open at their outer ends on two opposite sides, agitator blades secured to said shaft and cone and arranged in each slot eccentrically thereto and dividing the interior of the conical member at one side thereof.

4. In combination with a receptacle, a stirring or agitating appliance rotatable and vertically movable within the said receptacle, consisting of a vertical shaft extending through a central opening in the top of the receptacle and provided with a crank at its upper end, a cone secured to said shaft within the receptacle and provided with elongated slots open at their outer ends on two opposite sides, inclined agitator blades secured to said shaft and cone and arranged one in each slot eccentrically thereto, dividing the interior of the conical member at one side thereof and extending above the outer surface of the cone, and having inclined upper edges corresponding to the inclined surface of the cone.

5. In combination with a receptacle, a stirring or agitating appliance rotatable and vertically movable within the said receptacle, consisting of a vertical shaft extending through a central opening in the top of the receptacle and provided with a crank at its upper end, a conical member secured to said shaft within the receptacle and provided with elongated slots open at their outer ends on two opposite sides, agitator blades secured to the shaft and cone, one within each slot dividing the interior of the conical member at one side thereof and having a straight

vertical end edge extending above the outer surface of the conical member and a top edge inclined toward the shaft, the bottom of the said shaft, cone, and blades being on the same horizontal plane.

6. In combination with a receptacle, a stirring or agitating appliance rotatable within said receptacle and consisting of a vertical shaft within the receptacle extending from the bottom of the receptacle through a central opening in the top and provided with a crank on its upper end, a conical member secured to said shaft within the receptacle and provided on opposite sides with elongated slots open at their outer ends, agitator blades secured to the shaft and conical members dividing the interior of the cone at one side of each slot, the bottom edges of said conical members and blades being on the same horizontal plane with the lower end of the shaft.

7. In combination with a receptacle, a stirring or agitating appliance rotatable within said receptacle consisting of a vertical shaft extending through a central opening in the top of the receptacle and provided with a crank at its upper end, a conical member secured to the said shaft within the receptacle and provided with elongated slots open at their outer ends on two opposite sides, agitator blades, one within each slot and having at one end a tapered right-angled bend with a straight vertically inclined edge secured to the shaft whereby said blades are eccentrically arranged to cover one side of each slot.

8. The combination with a receptacle, of a depressed cover for the same provided at the center of the depression with a downwardly projecting tube having a bottom with a central opening therein, a gasket within said tube and resting upon its bottom, a plug fitting into said tube with its bottom contacting with said gasket, there being a central opening through said plug, a vertical shaft within the receptacle extending from the bottom of the receptacle through the central openings in the plug and tube, a crank upon the upper end of the shaft, a conical member secured to said shaft within the receptacle and provided with elongated slots open at their outer ends on opposite sides, and agitator blades within said slots projecting upwardly therefrom and dividing the interior of the cover at one side of each slot.

9. The combination with a receptacle, of a depressed cover for the same provided at the center of the depression with a downwardly projecting tube having a bottom with a central opening therein, a gasket within said tube and resting upon its bottom, a plug fitting into said tube with its bottom contacting with said gasket, there being a central opening through said plug, a vertical

shaft within the receptacle extending from the bottom of the receptacle through the central openings in the plug and tube, a crank upon the upper end of the shaft, a conical member secured to said shaft within the receptacle and provided with elongated slots open at their outer ends on opposite sides, and agitator blades secured to said shaft and conical member and arranged one

in each slot eccentrically thereto and covering one side thereof.

Signed by me this 13th day of March, 1915.

ERNEST MEYER.
